GOLF CLUB CARRIER

Robert A. Carman, Denver, Colo.

Application April 30, 1957, Serial No. 45,953

Term of patent 14 years

(Cl. D34—5)

FIG. 1.

FIG. 2.

FIG. 5.

FIG. 3.

FIG. 4.

Figs. 1 and 2 are opposite elevational side views of a golf club carrier embodying my new design, Fig. 1 showing the supporting spike retracted and Fig. 2 showing it extended.

Fig. 3 is a top plan view.

Fig. 4 is a horizontal sectional view taken in the plane of the line 4-4 of Fig. 2.

Fig. 5 is an edge view from the handle side also showing the supporting spike retracted.

I claim:

The ornamental design for a golf club carrier, as shown.
